UNITED STATES PATENT OFFICE.

LEWIS A. KRUEGER, OF MASON CITY, IOWA.

INDICATOR-CARD SCALING-RULE.

1,215,663.

Specification of Letters Patent. Patented Feb. 13, 1917.

Application filed June 17, 1915. Serial No. 34,686.

To all whom it may concern:

Be it known that I, LEWIS A. KRUEGER, a citizen of the United States, residing at Mason City, in the county of Cerro Gordo, 5 State of Iowa, have invented certain new and useful Improvements in Indicator-Card Scaling-Rules; and I do hereby declare the following to be a full, clear, and exact description of the invention, such as will enable others skilled in the art to which it 10 appertains to make and use the same.

This invention relates to an indicator card scaling rule.

An object of the invention resides in the 15 provision of a rule by means of which an indicator card of a steam cylinder may be read to find the mean effective pressure.

A further object of the invention resides in so constructing the device that as the 20 scale is moved from one ordinate to the other on the indicator card the readings will be computed.

With these and other objects in view, such as will appear as the description progresses, 25 my invention comprises the combination and arrangement of parts as set forth in and falling within the scope of the appended claim.

Referring to the drawing:

30 Figure 1 is a plan view of the device constructed in accordance with the invention with the slide removed showing the characters thereon.

Fig. 2 is a similar view of a portion of 35 the device with the slide in place. Fig. 3 is a section on line 3—3 of Fig. 2, the section being taken through the slide.

Fig. 4 is a detail of the slide.

Fig. 5 is a fragmental sectional view, 40 taken through the slide.

Fig. 6 is an enlarged detail of a portion of the body of the device, showing the divisional marks thereon.

Fig. 7 is a fragmental detail showing the 45 device applied to an indicator card, the slide being in the position it will occupy previous to the movement across the first ordinate.

Fig. 8 is a similar view showing the slide in the position it will occupy previous to 50 its movement across the second ordinate.

Referring to the drawing wherein like parts are indicated by like characters throughout the several views:—

In the embodiment of my invention shown 55 in the drawing, I have illustrated a scale

which consists of an elongated body portion 1 which is wedge-shaped in cross section and has a slide 2 mounted thereon, which slide consists of a frame 3 having a pair of downwardly extending flanges 4 60 which extend into grooves 5 in the edges of the body portion 1 so that the slide may be moved upon the body portion. Secured to the inner face of one of these flanges 4 is a spring 6 which bears upon the edge of 65 the body portion 1. The glass has a hair line 8 thereon extending transversely of the body portion 1 and in alinement with the apex of a point 9 formed on the other of the flanges 4.

One edge of the body portion 1 is divided into an inch scale by the line 10, which inch scale is in turn divided into fractions of an inch, preferably sixty-fourths. The remainder of the body portion is set-off into 70 divisions by horizontal lines 11. The divisions being indicated by the characters 12 to 18 inclusive.

Each of these divisions is divided by means of vertical lines 19 into scales, there being two scales in each division. At the end of each scale in each division is a character 20 which indicates the scale of spring used on the indicator. The vertical lines 19 in each of the divisions are 75 designated by two horizontal rows of characters 21 and 22, the former row being located above the latter, which characters form the scale above referred to. These characters 21 and 22 indicate the length of the ordinates of the indicator card multiplied by the scale of spring and the hundredths are placed on one side of the vertical lines 19, while the tens and units are placed on the other side for convenience of 80 reading.

The spaces between the vertical lines 19 are divided into smaller subdivisions, as illustrated in the drawing, for convenience of reading, the number of subdivisions being equal to the difference between the number on one of the vertical lines in each of the divisions and the number on the next adjacent line. For instance 85 in the division 18 at the upper left hand corner of the body portion the number of marks between the sub-divisions 1150 and 90 1200 will be 50.

In Fig. 7 of the drawing I have illustrated the device as being used in taking the reading from an indicator card when an eighty scale of spring has been used and I have 95 100

therefore only illustrated the eighty scale for the sake of convenience. The device is put in place as illustrated in this figure with the edge of the body portion 1 parallel to the first ordinate and the line 23 in the same horizontal plane as the point 24 where the first ordinate intersects the steam line. At this time the hair line 8 of the slide will coincide with the line 23 and the point 9 will lie immediately over the point 24 on the indicator card. The body portion 1 is held in position and the slide moved throughout the length of the first ordinate until the point 9 on the slide reaches the point 25 where the first ordinate intersects the exhaust line of the card. The slide is then held in this position and the device moved to the next ordinate where the point 9 on the slide is brought into alinement with the point of intersection between the second ordinate and the steam line. The operation of the slide previously described is then repeated and this operation is continued until the slide has been passed across all of the ordinates. When this has been done the slide will have been moved to such position that the hair line alines with one of the vertical lines 19 or one of the sub-divisions therebetween. Suppose for instance it alines with the line 19 at which line the character 640 of the series 21 appears. It will be noted that the hundredths are on one side of the vertical line and the tens and units on the other side. This will produce a reading, thus the mean effective pressure in this particular case will be 64.0.

It will be noted from the drawing that when certain scales of spring are used the slide will be moved from the left to the right of the body portion of the device and when others are used it will be moved from the

right to left. This arrangement is followed for the sake of convenience.

It will thus be seen that I have provided a device by means of which the mean effective pressure may be readily found, which device will obviate the necessity for computing the said mean effective pressure, the steps in the computation being automatically performed by the movement of the slide upon the body portion of the device.

While I have illustrated and described a particular embodiment of my invention, I have merely done so for the sake of convenience and I do not wish to be limited to that particular embodiment as it is obvious that numerous changes may be made within the details of construction thereof without in any way departing from the spirit of the invention or exceeding the scope of the appended claim.

What I claim is:—

In an indicator card scaling rule, the combination with a body portion having a plurality of scales thereon, of a slide adapted to be moved on the body portion for a distance equal to the combined lengths of the ordinates of an indicator card and to co-operate with certain of the said scales to produce the reading of the mean effective pressures, said slide having a hair line arranged to travel over the scales as the scale moves and being provided adjacent the underside of the body with a pointer having its apex in vertical alinement with said hair line.

In testimony whereof, I affix my signature, in the presence of two witnesses.

LEWIS A. KRUEGER.
